(57) **CLAIM**

The ornamental design for an automated ball-throwing apparatus, as shown and described.

DESCRIPTION

FIG. 1 is a perspective view of an automated ball-throwing apparatus according to my new design;

FIG. 2 is a right side view thereof;

FIG. 3 is a left side view thereof;

FIG. 4 is a back view thereof;

FIG. 5 is a front view thereof;

FIG. 6 is a top plan view thereof; and,

FIG. 7 is a bottom plan view thereof.

The broken lines shown in the drawings depict environmental subject matter and form no part of the claimed design.

1 Claim, 7 Drawing Sheets
